UNITED STATES PATENT OFFICE

2,307,306

TRACK SANDER

William L. Seaman, Pittston, Pa.

Application January 16, 1942, Serial No. 427,068

3 Claims. (Cl. 291—41)

The invention relates to improved track sanding means, and the primary object of the invention is to provide an arrangement of this character wherein the sand dispensing hoses are caused to follow the deflection of the wheels of the locomotive or the like, relative to the tracks, as in negotiating a turn, whereby the waste and misapplication of the sand to one or the other side of the tracks which commonly takes place in present arrangements of this character is eliminated, and the sand is efficiently and continuously applied to the tracks in front of the wheels.

Other objects and advantages of the invention will be apparent from a reading of the following description taken in connection with the appended drawings, wherein a preferred embodiment of the invention is shown.

In the drawings:

Figure 1 is a fragmentary side right hand side elevational view of a railway locomotive equipped in accordance with the present invention.

Figure 2 is a fragmentary transverse vertical sectional view taken through Figure 1 along the line 2—2 and looking in the direction of the arrows with portions of the locomotive shown in phantom lines.

Figure 3 is a fragmentary enlarged and contracted front elevational view of the track sanding arrangement.

Figure 4 is a horizontal sectional view taken through Figure 3 along the line 4—4 and looking downwardly in the direction of the arrows.

Figure 5 is an enlarged fragmentary transverse vertical sectional view taken along the line 5—5 of Figure 3 and looking toward the left in the direction of the arrows.

Figure 6 is a fragmentary transverse vertical sectional view taken through Figure 3 along the line 6—6 and looking toward the left in the direction of the arrows.

Referring in detail to the drawings, numerals 5 and 6 generally designate similar vertically elongated brackets which are welded or otherwise suitably secured to depend from the forepart of the frame or chassis of the locomotive 7 between 45 the front portions of the front drive wheels 8 as indicated in Figure 1 of the drawings, the brackets 5 and 6 being transversely spaced between the drive wheels 8 and equipped on their lower ends with L-shaped terminals 9 with cotter keys or the like 10 passed through openings 11 and 12, respectively, formed in the upper end of the standard portion of the terminal 9 and a point of corresponding elevation on the body of the bracket as indicated in Figure 5 of the draw-

ings, the purpose of the terminals 9 and the cotter keys 10 being to retain for horizontal lateral sliding support the slide bar which is generally designated 13 which is of generally rectangular cross-section, with a length adjusting turnbuckle 14 connected in the slide bar between the brackets 5 and 6 as indicated in Figures 3 and 4.

Laterally outwardly beyond the brackets 5 and 6 the slide bar 13 has threaded terminals 15 on which are longitudinally adjustably threaded the clevises 16 between whose arms are carried the rollers 17 which bear against the inner sides of the marginal portions of the front drive wheels 8.

The portions of the slide bar 13 between the adjacent brackets and the roller equipped clevises have welded or otherwise secured thereto the forwardly and downwardly and laterally outwardly bent arms 18 whose laterally outward terminals are pivoted as indicated by the numerals 19 between the pairs of ears 20 on the downwardly and rearwardly curved auxiliary sand discharging pipes 21 which reach down to the tracks 22 as indicated in Figures 1 and 2 to discharge the sand on the rail head in front of the forward driving wheels 8.

The auxiliary sand discharging pipes 21 are connected in communication with the regular equipment sand distributing pipes 24 which depend from the locomotive chassis in front of the front drive wheels, by a flexible coupling 24 which permits the auxiliary pipes 6 and 21 to be pivoted and laterally deflected by the connection of the arms 18 thereto, in response to the shifting motion of the slide bar 13, produced by the deflection of the wheels 8 in contact with the rollers 17 on the opposite ends of the slide bar. As the wheels 8 are deflected relative to the locomotive chassis the slide bar 13 is adjusted to keep the lower end of the auxiliary sand discharging pipes 21 positioned to deposit the sand on the rail head.

Although there is shown and described herein a preferred embodiment of the invention it is to be understood that the invention is not confined thereto except as provided by the subjoined claims.

Having described the invention, what is claimed as new is:

1. A track sander for a railway vehicle having drive wheels and a frame having a stationary sand discharging pipe depending from said frame in front of a drive wheel on a track rail, said sander comprising a transverse slide bar, bracket means suspending said slide bar from said frame, roller means on said slide bar rollably engaged with a portion of each of the drive wheels where-

by the slide bar is moved longitudinally of its length in conformity with the lateral deflection of said drive wheels with respect to said rail in the travel of the vehicle, an auxiliary sand discharge pipe having its lower end disposed to discharge sand upon the rail in front of one of said drive wheels, a flexible coupling connecting said auxiliary pipe with the lower end of said permanent pipe, and an operating connection between said auxiliary pipe and said slide bar.

2. A track sander for a railway vehicle having drive wheels and a frame having a stationary sand discharging pipe depending from said frame in front of a drive wheel on a track rail, said sander comprising a transverse slide bar, bracket means suspending said slide bar from said frame, roller means on said slide bar rollably engaged with a portion of each of the drive wheels whereby the slide bar is moved longitudinally of its length in conformity with the lateral deflection of said drive wheels with respect to said rail in the travel of the vehicle, an auxiliary sand discharge pipe having its lower end disposed to discharge sand upon the rail in front of one of said drive wheels, a flexible coupling connecting said auxiliary pipe with the lower end of said permanent pipe, and an operating connection be-

tween said auxiliary pipe and said slide bar, said slide bar incorporating means to adjust its length and said bracket means permitting relative limited up and down motion of said slide bar.

5 3. A track sander for a railway vehicle having drive wheels and a frame having a stationary sand discharging pipe depending from said frame in front of a drive wheel on a track rail, said sander comprising a transverse slide bar, bracket means suspending said slide bar from said frame, roller means on said slide bar rollably engaged with a portion of each of the drive wheels whereby the slide bar is moved longitudinally of its length in conformity with the lateral deflection of said drive wheels with respect to said rail in the travel of the vehicle, an auxiliary sand discharge pipe having its lower end disposed to discharge sand upon the rail in front of one of said drive wheels, a flexible coupling connecting said auxiliary pipe with the lower end of said permanent pipe, and an operating connection between said auxiliary pipe and said slide bar, said operating connection comprising an arm projecting rigidly from said slide bar and having pivotal connection with said

20 25 auxiliary pipe.

WILLIAM L. SEAMAN.
